CLAIM

The ornamental design for a hinged-lid box, as shown and described.

DESCRIPTION

FIG. 1 is an upper perspective view of a hinged-lid box embodying our new design;

FIG. 2 is a front side elevation view thereof;

FIG. 3 is a rear side elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The lightweight dash-dash broken line portion of the figure drawings is included to show unclaimed subject matter only and forms no part of the claimed design.
